UNITED STATES PATENT OFFICE.

JOHN M. COLUCCI, OF BROOKLYN, NEW YORK.

DESIGN FOR A SMOKING STAND.

Application filed June 12, 1928. Serial No. 27,092. Term of patent 7 years.

To all whom it may concern:

Be it known that I, JOHN M. COLUCCI, a citizen of the United States, residing in Brooklyn, county of Kings, and State of New York, have invented a new, original, and ornamental Design for a Smoking Stand, of which the following is a specification, reference being had to the accompanying drawing, forming part thereof, in which—

for smoking stand.

I claim:

The ornamental design for a smoking stand, as shown.

JOHN M. COLUCCI. [L.S.]
